UNITED STATES PATENT OFFICE.

GEORG FERRY VOLTZ, OF HORNAU, GERMANY, ASSIGNOR TO THE FIRM OF ERNST PAUL LEHMANN, OF BRANDENBURG-ON-THE-HAEL, GERMANY.

TOY.

1,073,880.

Specification of Letters Patent. Patented Sept. 23, 1913.

Application filed August 19, 1911. Serial No. 644,906.

To all whom it may concern:

Be it known that I, GEORG FERRY VOLTZ, subject of the King of Prussia, residing at Hornau, in the Kingdom of Prussia, Germany, have invented new and useful Improvements in Toys, of which the following is a specification.

My invention relates to an improved toy, which may also be employed as an instructive model in teaching physics, its function being derived from the gyroscopic principle. By the aid of said principle a toy vehicle or car mounted on two or more wheels placed in line or approximately in line behind each other may be made to run, being maintained in a state of equilibrium by the power of gyration, without which the vehicle or car would at once tumble down by the want of support on its line of motion.

20 The object of my invention is to construct a toy-vehicle or car according to said principle.

In order to make my invention properly understood, I have illustrated the same in the accompanying drawing, in which:

Figure 1 is a side-elevation of a car, partly in section, provided with the apparatus of my invention. Fig. 2 is a plan of a part of the said apparatus with the top removed. Fig. 3 is a front-view of the same in transverse section on line A—B of Fig. 1, parts being shown in elevation; and Fig. 4 is a side-view of the lower part of the apparatus, seen from the side opposite to that shown in Fig. 1.

Referring to Figs. 1 to 4, *r* is a car of any suitable shape or construction, mounted on two wheels *c*, and *s*, in line behind each other with a suitable distance between them, the front-wheel *c*, being the steering wheel while the other wheel *s* only serves to support the rear portion of the car. The said steering-wheel *c* has its axle carried in the sides of a frame *b* having an upper trunnion *b*¹ and a lower trunnion *b*², the latter being carried by a cross stay *b*³ between the two sides of said frame *b*. Bearings are provided for the said trunnions *b*¹ and *b*² in the flattened ends of a rod *d*, forming a bow and secured to the bottom of the car by means of a plate *h* or any other suitable means. The said bow *d*, thereby, is rigidly held in position and the frame *b*, arranged to turn between the two ends of said bow, 55 forming bearings for the trunnions *b*¹ and

*b*². The supporting frame *b* extends through a suitable aperture in the bottom of the car *r*, and across the upper portion of the said frame *b* extends the axle *x* of the gyrator or revolving fly-wheel *a*, the ends of the axle *x* being pointed for reducing friction and supported in corresponding bearings in a well known manner, as fully shown in Figs. 2, and 3. It will be seen, then, that the frame *b*, holding within its upper portion the gyrator *a*, and within its lower end the steering-wheel *c*, forms a rigid connection between the said gyrator and wheel *c*, holding them constantly in the same plane but allowing free and independent rotatory motion to either of them. The said gyrator *a*, and steering wheel *c*, might as well be supported by separate frames or forks, not integral with each other, in such case the two frames or forks must be rigidly secured to each other and their planes coinciding with each other. A single frame *b*, as shown, holding both the gyrator and the steering wheel *c*, is preferred as best answering the purpose in view.

In using the toy, rotatory motion of great speed is imparted to the gyrator *a*, by any suitable means, such, for instance, as shown in Fig. 3, consisting of a train of wheels and pinions carried by a frame side secured to one side of the frame *b*. A suitable key of a known kind, turned by a crank or handle is placed on the square portion *g*, of one of the axles of the train of wheels, thus transmitting rotatory motion of a multiplied speed to the gyrator, while low speed, at the same time, is imparted to the steering wheel *c*. On starting the car or vehicle *r* by placing it on its supporting surface and giving it a starting push in the direction of its intended motion, the said gyrator *a*, by its momentum and great speed upholds the car and prevents its tumbling or losing its state of equilibrium.

As stated before, the means of imparting rotatory motion of great speed to the rotator or gyrator *a*, may be varied, as desired. The train of gear-wheels shown may be replaced by clock-work driven by a spring, or a cord wound up to the axle *x* of the gyrator may serve to impart motion to said gyrator by being rapidly wound off, in the well-known manner employed in starting toy-tops. Any other driving means might as well be employed, and if the driving

power is only made to actuate the gyrator, the rotatory motion of the gyrator may be transmitted to the steering wheel *c*, by any suitable means, such as gearing or friction 5 wheels or the like. Instead of making the car travel on by imparting driving power to the front- or steering wheel *c*, such driving power might as well be applied to the rear wheel *s*, and separate, independent driving means, such as a spring-driven clock-work or motor of any kind might be employed to make the car travel. Or it might be caused to move on by the aid of a screw-propeller or the like, independent of the 10 wheels.

I claim as my invention:

1. In a wheeled toy, in combination, a gyrator, a wheel on which the toy travels, said gyrator and wheel being mounted to rotate 20 in substantially the same plane, and actuating gearing arranged to drive said gyrator and said wheel.

2. In a wheeled toy, in combination, a gyrator, a wheel on which the toy travels, said gyrator and wheel being mounted to rotate 25 in substantially the same plane, and actuating gearing arranged to drive said gyrator and said wheel at different rates of speed.

3. In a wheeled toy, in combination, a gyrator, a steering wheel, suitable axles carrying said gyrator and said steering wheel, a frame rigidly connecting said axles whereby said gyrator and said steering wheel are compelled to rotate in substantially the same plane, and gearing arranged to impart motion at different rates of speed to the gyrator and the steering wheel. 35

In testimony whereof I have signed my name to this specification in the presence of two subscribing witnesses.

GEORG FERRY VOLTZ.
